UNITED STATES PATENT OFFICE.

LEE HOYT LE CLAIRE, OF DENVER, COLORADO, ASSIGNOR TO THE LE CLAIRE
BRANDING IRON COMPANY, A CORPORATION OF COLORADO.

BRANDING APPARATUS.

984,768.

Specification of Letters Patent. Patented Feb. 21, 1911.

Application filed April 29, 1910. Serial No. 558,399.

To all whom it may concern:

Be it known that I, LEE HOYT LE CLAIRE, a citizen of the United States, residing in the city and county of Denver and State of Colorado, have invented certain new and useful Improvements in Branding Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in branding apparatus and consists of a special construction of branding iron, connected with a conduit, the latter leading to a receptacle containing gasoline or other sufficiently volatile liquid for the purpose, the extremity of the conduit opposite the tool being equipped with a compressible bulb adapted to force air into and through the liquid receptacle, whereby the liquid is vaporized and the vapor aerated to produce a readily combustible mixture which is carried to the branding tool proper where it is initially ignited, after which the combustion is maintained as long as the tool is supplied 30 with the combustible mixture.

The branding apparatus is portable, being mounted on a belt worn by the user, the liquid receptacle being carried by the belt, which is also equipped with pockets adapted 35 to receive the tool and bulb when not in use, the belt having loops to support the conduit which extends around the belt.

Having briefly outlined my improved construction, I will proceed to describe the same 40 in detail, reference being made to the accompanying drawing in which is illustrated an embodiment thereof.

In this drawing: Figure 1 is a front view of my improved branding apparatus, the 45 supporting belt being shown in perspective and the branding devices mounted thereon or connected therewith. Fig. 2 is a sectional view in detail showing the branding device proper, and on a larger scale. Fig. 3 is a 50 sectional view in detail showing the branding tip or iron on a still larger scale. Fig. 4 is a sectional view taken through the liquid receptacle and illustrating its connection with the conduit, whereby air is forced there-

into and the combustible mixture carried to 55 the branding iron, the parts being shown on a larger scale than in Fig. 1.

The same reference characters indicate the same parts in all the views.

Let the numeral 5 designate a belt adapted 60 to be fastened around the waist, and for this purpose equipped with buckles 6 and co-operating straps 7. This belt is equipped with a pocket 8 adapted to contain a gasoline receptacle 9. Into the top of the receptacle is screwed a hard rubber plug 10 in which are formed passages 12 and 13, the plug having lateral extensions 14 and 15 through which these passages are continued, the said extensions forming threaded nipples 65 70 to which short hard rubber tubes 14^a and 15^a are attached and over which the inner extremities of the flexible conduits 16 and 17 are slipped and held tightly in place thereon.

The conduit member 16 has a compressible 75 bulb 18 at its free extremity, the said bulb being adapted, when pressed, to force air into the receptacle 9 for the purpose of atomizing the volatile liquid therein and forming a combustible mixture which is 80 forced outwardly through the conduit 17 whose free extremity is slipped over the hard rubber nipple 19 screwed upon one extremity 20 of a tube 21 passing through a 85 hollow handle 22. Into the opposite extremity of this tube 21 is screwed the branding iron or tip 23 which terminates in a hollow approximately semispherical member 24 having perforations 25 to permit the escape 90 of the combustible mixture, the part 24 extending upwardly beyond the perforations 25 as shown at 26 and forming a circular depression 27 co-operating with the corresponding depression or chamber 28 formed in an approximately semispherical deflector 29 95 screwed upon the threaded shank 30 of the branding tip. The depressions 27 and 28, co-operate to form a combustion chamber communicating with the atmosphere through a space 31 interposed between the two members of the tip to permit the escape of the 100 products of combustion.

When the device is not in use the bulb 18 may be inserted and carried in a pocket 32 and the branding iron and its handle in a 105 pocket 33, both of which are mounted on the belt and provided with hinged lids or covers 34 and 35. Also mounted upon this belt is

a lamp carried in a pocket 36 and having a protruding burner 37 which may be employed for the initial heating of the tip preparatory to the ignition of the combustible mixture. This heating of the tip is necessary since the mixture is not sufficiently gassed to readily ignite. The tip is therefore initially heated before supplying the combustible mixture thereto.

When the device is in use, the belt 5 is not only buckled around the waist of the user but is also further supported by the straps 38 which pass over his shoulders. The lamp 37 may first be lighted by the use of an ordinary match, after which the tip is heated from the lamp to the necessary degree. The combustible mixture, composed of air and vaporized gasolene, as heretofore explained, is then delivered to the tip by the manipulation of the bulb 18 and this supply is continued in order that the temperature of the tip may be maintained at the necessary degree for branding purposes.

By adjusting the deflector 29 upon the threaded shank 30 of the branding tip, the size of the combustion chamber 28 may be regulated at will.

Having thus described my invention, what I claim is:

1. A hollow branding iron or tip, having its exterior surface convex and its inner surface concave and perforated for the escape of combustible mixture, the said tip having a threaded shank and a deflector threaded on said shank and having its inner surface concave to coöperate with the concavity of the tip proper, whereby a combustion chamber is produced whose capacity may be regulated at will.

2. A branding device, comprising a hollow tip of semispherical shape, having its outer surface convex and its inner surface concave and perforated for the escape of combustible mixture, the tip having an exteriorly threaded shank in communication with its hollow portion, a deflector threaded on said shank and having its inner surface concave to coöperate with the adjacent concavity of the tip to form a combustion chamber, a hollow handle detachably connected with the shank of the tip, and means for

passing a combustible mixture through said handle to the tip, for the purpose set forth.

3. A branding device, comprising a hollow tip having a shank and equipped with an adjustable coöperating deflector, the inner surface of the tip being concave and perforated for the escape of combustible mixture, a hollow handle connected with the shank of the tip which is threaded for the purpose, a flexible conduit connected with said handle, a receptacle for combustible fluid to which the conduit leads, a second conduit leading from the said receptacle, and a compressible bulb connected with the second conduit for forcing air through the fluid receptacle, for the purpose set forth.

4. The combination with a fluid receptacle having flexible conduit sections in communication therewith, a compressible bulb connected with one conduit section, and a hollow concave branding tip connected with the other conduit section and in communication therewith, the branding tip having a threaded shank equipped with a deflector whose inner surface is concave, and coöperating with the concavity of the tip to form an adjustable combustion chamber for the consumption of the aerated mixture delivered thereto.

5. The combination with a fluid receptacle, having flexible conduit sections in communication therewith, a compressible bulb connected with one section, and a hollow, handle member connected with the other section and in communication therewith, a hollow, concave branding tip, connected with the handle member and in communication with the pipe section through the hollow of the handle member, the branding tip having a threaded shank equipped with a deflector whose inner surface is concave and coöperating with the concavity of the tip to form an adjustable chamber for the consumption of the aerated mixture delivered thereto.

In testimony whereof I affix my signature in presence of two witnesses.

LEE HOYT LE CLAIRE.
